UNITED STATES PATENT OFFICE

IRA M. PETERSIME, OF GETTYSBURG, OHIO

FOLDING WALKER

Application filed February 10, 1930. Serial No. 427,389.

This invention relates to exercisers or walking apparatus for use in bedrooms, bathrooms and other places where apparatus of this kind can be conveniently used and where the space is small.

It is the object of this invention to provide an exerciser or walking apparatus in which the main frame is formed of two parts pivotally connected together so that one part 10 may be folded upon the other for the purpose of storage, with the handle telescoped therein, and when so folded the whole apparatus may be placed under a small table, or other similar article where the space is 15 small.

It is particularly the object of this invention to provide an exerciser or walker equipped with a traveling belt operated by a motor. This belt is adapted to receive a person 20 thereon, and during the operation of the motor the belt travels and the person on the belt walks to prevent falling, and for the purpose of aiding in preventing the falling of the person on the belt a support is provided near one end of the frame.

There is shown in the accompanying drawings a preferred embodiment of this invention.

Referring to the drawings:

Figure 1 is a side elevation.

Figure 2 is a front end view.

Figure 3 is a view similar to Figure 1, with the exception that the rear is folded upon the front part of the apparatus.

Figure 4 is a top plan view with the traveling belt partly removed.

Figure 5 is a section on the line 5—5 of Figure 4.

This apparatus is composed of a frame member formed into two sections, a front section and a rear section. The frame as a whole is substantially rectangular and has side walls 1 on each side of the front section, which extend forward, as indicated by the 40 numeral 1', to form supports for a platform. The rear section has side walls 2. These sections are united by invisible hinges 3. These 45 hinges are so attached to the two sections that they are substantially out of sight, and enable the frame to be either in the extended

position shown in Figure 1 or in the folded position shown in Figure 3. The rear side members are connected at the rear end of the frame by means of a rear wall 4, while the front side members are connected by a front 55 wall 5.

The platform on the front part of the front side walls is indicated by the numeral 6, and supports a motor 7 which has a shaft 8. On the end of the shaft is a pulley 9 60 for the purpose of operating the apparatus. On the rear of the frame is a drive roller 10 supported in the side walls by means of trunnions 11. This roller is in the rear end of the rear section, and has extending therefrom a shaft carrying a pulley 12. This shaft is a continuation of one of the trunnions that supports the ends of this roller. From the pulley 9 to the pulley 12 extends 65 a belt 13 for the purpose of rotating the roller 10, due to the operation of the motor 7.

On the front end of the front side walls is a front roller 14 of substantially the same size that roller 10 is, and between these two rollers is a series of transversely arranged 70 belt-supporting rollers 15, which are smaller in diameter than the rollers 10 and 14 but have their upper surfaces in line with the upper surfaces of rollers 10 and 14 for the purpose of supporting the belt 16 in a 75 straight horizontal position.

Suitably arranged adjacent the motor is a handle bar 17. For the purpose of receiving the ends of this handle, which is U-shaped, there are sockets 18. The handle bar is located within these sockets so that the person standing on the traveling belt may balance himself and prevent falling when the belt is traveling, due to the operation of the motor. In the folded position 90 this handle bar is in the position shown in Figure 3, and for that purpose there is provided in the rear section sockets 19 which receive the ends of the handle bar for folding purposes.

As shown in Figure 3 the apparatus is in folded condition so that it may be placed under a small table, or any other place where there is a small amount of room, for the purpose of getting the apparatus out of the 100

way or out of sight until it is needed for use again. When the apparatus is needed it is removed from its place of storage, the rear section is folded backward so that it 5 rests in line with the front section, as shown in Figure 1. At this time the belt 13 is engaging the two pulleys 7 and 12.

Upon the operation of the motor the belt 16 is caused to travel in a rearward direction 10 over the supporting rollers 15, and in order to balance himself upon the traveling belt the person standing thereon walks forward with his hands upon the upper end of the handle bar. This operation is continued 15 a sufficient length of time to give the person the desired or required amount of exercise, after which the motor is cut off, the apparatus folded and stored in its accustomed position. The hinges 3 are so located 20 that they are substantially out of sight, both when the frame is in its extended position and when it is in its folded position. By that means they afford no obstruction to the feet of the person standing upon the tread 25 or traveling belt during the process of exercise.

I desire to comprehend within my invention such modifications as may be clearly embraced within my claims and the scope of 30 my invention.

Having thus fully described my invention, what I claim is new and desire to secure by Letters Patent, is:

1. In a folding walker, a portable frame 35 having sections adapted to fold one on the other, a platform extending from one section, a motor on said platform, a roller on opposite ends of each section, a belt on said rollers adapted to be moved thereby, idler 40 rollers on said frame engaging the underside of the upper loop of said belt, means connecting the motor to one of the end rollers for causing the belt to travel, and a hand support on one of said sections.

2. In a folding walker, a portable frame formed of sections pivoted one to another and adapted to be folded one upon the other, a plurality of rollers mounted in each section, a belt on said rollers, a motor supported on one of said sections, and means connecting said motor to one of said rollers for causing said belt to travel.

3. In a folding walker, a frame composed 55 of pivotally united sections adapted to fold one on another, a roller mounted on each section, a belt on said rollers, means to rotate one of said rollers to cause the belt to travel, and a hand support adjacent said belt.

4. In a folding walker, a frame composed 60 of pivotally united sections normally in extended aligned position but adapted to be folded one on another, a roller mounted on 65 each of the opposite ends of said frame, a

belt around said rollers adapted to travel as the rollers rotate, means for causing the rollers to rotate, and a U-shaped hand support extending up from one section when the sections are in extended condition and supported by the other section parallel to the first section when the sections are folded.

5. In a folding walker, a frame composed of sections pivoted to each other, said frame being normally in an extended condition but 70 adapted to be folded with one section on the other, one section having in one end a pair of vertical holes and the other section a pair of horizontal holes in one end, a traveling member supported by said frame 75 and adapted to be folded with the frame, means to cause said traveling member to travel, and a U-shaped hand support adapted to be supported by the first-named holes when the frame is in extended condition and adapted to be supported by the last-named holes when the frame is in 80 folded condition.

In testimony whereof, I affix my signature.

IRA M. PETERSIME.
